UNITED STATES PATENT OFFICE

JAMES M. MATHEU, OF NEW YORK, N. Y., ASSIGNOR TO UNITED SHOE MACHINERY CORPORATION, OF PATERSON, NEW JERSEY, A CORPORATION OF NEW JERSEY

MACHINE FOR SHAPING UPPERS OVER LASTS

Application filed February 4, 1930, Serial No. 425,882. Renewed June 18, 1932.

This invention relates to machines for use in the manufacture of shoes for shaping uppers over lasts. The invention is herein illustrated in its application to what is known as a pulling-over machine, although in its more general aspects it is not limited to machines of that particular kind.

An object of the invention is to provide a machine of the above-mentioned character especially adapted for use in the manufacture of stitchdown shoes in which the margin of the upper, at least around the forepart and in the shank, is turned outwardly from the last and is secured in that position to the projecting margin of a sole which is larger than the bottom face of the last. For the purpose in view the machine herein shown comprises means for shaping the upper over the last, as illustrated, by pulling it at the end of the toe and the opposite sides of the forepart in one operation, and means for driving upper-holding fastenings through the upper and into the last in different locations about the forepart in such relation to the bottom face of the last as to permit the margin of the upper to extend outwardly upon the projecting margin of a sole while the fastenings are in upper-holding positions. More particularly, the illustrated machine comprises grippers for pulling the upper in the above-mentioned locations with its margin extending heightwise of the last, and a plurality of tackers which are movable relatively to the grippers into upper-fastening positions at the end of the toe and the sides of the forepart and are constructed and arranged to drive tacks part way into the shoe and last in locations substantially at the junction of the bottom face and the upper-shaping surface of the last and at inclinations to the bottom face such as to permit the margin of the upper, with only a small amount of bending of the tacks, to be turned outwardly far enough to lie upon the projecting margin of a sole applied over the bottom of the last. The pulling-over tacks are accordingly so located in relation to the last and shoe that while holding the upper closely in the angle between the last and the projecting margin of the sole they may remain in

place until the outturned margin of the upper has been permanently secured to the sole.

The invention is herein illustrated by reference to the manufacture of stitchdown shoes of a type in which the margin of the upper is secured in outturned position to a so-called first sole which lies next to the last and is larger than the bottom face of the last and upon which an outsole is applied before the completion of the shoe. In the manufacture of stitchdown shoes of this and other types it has been a common practice heretofore to last the shoe progressively by conforming different portions of the loose upper in succession to the contour of the last and fastening them to the sole in the angle between the last and the projecting margin of the sole. By the use of a machine constructed as herein disclosed the upper is stretched more uniformly and effectively over the last than is possible in such a progressive lasting operation, with a resulting improvement in the quality of the shoe and also with a substantial saving in upper stock, since by reason of the more effective stretching of the upper it may be cut to a smaller pattern than heretofore. Such a pulled-over shoe, moreover, under some manufacturing conditions, may be presented to a sewing machine whereby the margin of the upper is secured permanently to the sole, without any further lasting of the pulled-over portions of the upper other than that performed in the operation of such a machine.

While the invention is illustrated with particular reference to the manufacture of stitchdown shoes having the characteristics above described, it is not limited to the manufacture of shoes of that particular type, and it is accordingly to be understood that the term "sole" as frequently used in the claims is intended to designate that part to which the outturned margin of the upper is secured, whether it be the "first sole" of a shoe of the above-mentioned type or some other shoe bottom part characteristic of a different type of stitchdown shoe.

The novel features of the invention will now be more particularly described by refer-

ence to the accompanying drawings and thereafter pointed out in the claims.

In the drawings,

Fig. 1 is a view from the front, partly in section, of a portion of a machine in which the invention is embodied, comprising means for pulling and fastening the upper at the opposite sides of the forepart, the parts being shown substantially in the positions that they 10 occupy at the time of the upper-fastening operation;

Fig. 2 is a view similar to a portion of Fig. 1, but showing the parts in the positions that they occupy at the time of the pulling of the 15 upper;

Fig. 3 is an inverted plan view of one of the side tackers and associated parts;

Fig. 4 is a view substantially in side elevation, but with the parts at a different angle 20 than in the actual machine, showing the upper-fastening mechanism at the left-hand side of the shoe (Fig. 1) as it appears when viewed from the right;

Fig. 5 is a view in side elevation of the 25 upper-pulling and fastening mechanism at the end of the toe;

Fig. 6 is a perspective view of a last and upper after the upper has been pulled over and fastened by the machine; and

30 Fig. 7 is a cross-sectional view of the last and shoe after a sole has been applied on the bottom of the last.

The invention is illustrated in its application to a pulling-over machine of a well-known type, the main features of the general organization of which are disclosed in Letters Patent No. 1,029,387, granted on June 11, 1912, upon an application of R. F. McFeely. Only such parts of the machine, therefore, as 35 40 it is necessary to refer to for an understanding of this invention are shown and will be described in detail.

For positioning the work and supporting the last against the pull applied to the upper, the machine is provided with a work rest 10 which in the operation of the machine on a shoe of the character illustrated directly engages the bottom face of the last. For pulling the upper at the end of the toe and the 45 50 opposite sides of the forepart, there are provided a toe gripper 12 (Fig. 5) and opposite side grippers 14 (Fig. 1). When the operator presents the work to the machine he positions the margin of the upper within the open 55 60 jaws of the toe and side grippers and then starts the machine, whereupon the grippers are operated by power to pull the upper over the last with its margin extending generally heightwise of the last, as illustrated in Fig. 60 65 70 75 80 85 90 95 100 105 110 115 120 125 130 135 140 145 150 the driver, this slide having thereon a pin 38 engaged by the forked lower end of the driver bar 26. Clamped on the lower end of the arm 20 by a spring 40 are two fingers 42 which serve as a tack holder and are recessed in their opposed faces to provide a tack pocket 44 into which each tack is fed through a passage 46 in the arm 20, this arrangement being somewhat similar to the disclosure of Letters Patent No. 1,279,491, granted on September 24, 1918, upon an application of Orrell Ashton. To determine further such a relation between the tack holder and driver and the shoe that the tack will be driven in the location above described, there is secured on the lower end of the arm 20 by a clamping screw 46 a member 48 one end of which acts as a stop in engagement with the shoe to limit the movement of the arm. A slot 50 in the member 48 permits adjustment of the member to determine precisely the required location of the tack. The member 48 serves also as a clamp to hold the upper on the last against loss of tension after it has been released by the toe gripper. To assist in holding the upper and in positioning it properly to receive the tack, the arm 20 also carries a wiper 52 which bends the margin of the upper inwardly over the bottom of the last, the wiper having on one side a down-turned flange 54 which is clamped to the arm 20 by the screw 46 between the side of the arm and the member 48.

For driving the side tacks, each side arm 22 carries two plates 56 (Figs. 1 and 4) in each of which is provided a guideway for a tack driver 58 arranged at the required inclination. Similarly to the means above described for fastening the upper at the end of the toe, each plate 56 is provided with tack holder fingers 60 controlled by a spring 62 (Figs. 1 and 3) and cooperating to form a tack pocket 64 (Fig. 4), an adjustable limiting and upper-clamping stop 66 secured to the plate by a clamping screw 68, and a wiper 70 having a flange 72 (Fig. 4) also clamped to the plate 56 by the screw 68. In each plate 56 is a passage 74 through which a tack is fed to the tack pocket 64 from a corresponding delivery tube 76 (Fig. 1) when the arm 22 is in its idle position. The two plates 56 are not fast on the arm 22, but are so mounted as to permit relative movement between them and also between each plate and the arm so that they will assume relative positions determined by the last before the driving of the tacks. For this purpose each plate is provided with slots 78 and 80 extending laterally of the shoe, and through the respective slots project bolts 82 and 84 which serve as guides, the slots being somewhat larger heightwise of the shoe than the diameters of the bolts, so that the plate may rock in response to the action of the shoe on the wiper 70. The bolt 82, as illustrated in Fig.

4, extends through the arm 22 and also through a plate 86 which is fast on the arm, the bolt having a shoulder at 88 whereby it serves to clamp the plate 86 to the arm when a nut 90 on the end of the bolt is tightened. It will be understood that the bolt 82 extends through the slots 78 of the two plates 56, one of these plates being spaced from the plate 86 by a sleeve 92 and the two plates being spaced apart by a sleeve 94, these sleeves being so formed as to permit the plates 56 to move freely. The bolt 84 which extends through the slots 80 is not seen in Fig. 4, since it is located behind the bolt 82, but it will be understood that this bolt is secured to the fixed plate 86 and that spacing sleeves similar to the sleeves 92 and 94 are provided thereon. The plate 86 is further secured to the arm 22 by a bolt 96. Mounted on a rod 98 on the plate 86 is a torsion spring 100 the two ends of which are arranged to bear respectively on the two plates 56 to force the plates normally inward and downward as far as permitted by the bolts 82 and 84. It will be understood that this spring controls the plates as the arm 22 is swung toward the shoe, permitting the two tackers to adjust themselves in proper relation to the shoe, the movement of the arm being finally limited by one or the other of the plates when the bolts 82 and 84 arrive at the inner ends of the slots in that plate.

Each of the tack drivers 58 has a clamp 102 fast on its outer end, and this clamp is pivoted on a stud 104 carried by an arm 106 which is pivoted at 108 on the adjacent plate 56, the two arms 106 of each pair of side tackers being adjacent to each other, as illustrated in Fig. 4. Each of the two arms 106 has a slot into which projects a pin 110 carried by a bracket 112 which is secured by studs 114 to the driver bar 28. Accordingly it will be understood that when the driver bar is moved downwardly the pin 110 acts on both the arms 106 to swing them about the studs 108 and thus to operate the drivers 58 to drive the tacks. The guideways in the plates 56 for the drivers 58 are sufficiently large to permit such small lateral movements of the drivers as are necessitated by the swinging of the arms 106. It will be evident that the pin-and-slot connections between the bracket 112 and the arms 106 permit the plates 56 and the parts carried thereby to adjust themselves to the shoe in the manner hereinbefore described.

The operation of the machine will be fully understood from the foregoing description. It will be seen that the several tacks are driven in locations slightly beyond the extremity of the bottom face of the last, at what may be termed the junction of the bottom face with the upper-shaping surface of the last, and at such inclinations to the bottom face that with only a small amount

of bending of the tacks, without loosening their hold in the last, the margin of the upper *b* may be turned outwardly far enough to lie upon the projecting margin of a sole *c* (Fig. 7) applied on the bottom of the last while the tacks are in upper-holding positions. In the particular shoe herein illustrated the sole *c* is what is known as a first sole to which the margin of the upper is permanently secured and over which an out-sole is thereafter applied. It is contemplated that after the margin of the upper has thus been turned outwardly and the sole *c* tacked to the last, the shoe herein shown will be taken to a machine whereby the margin of the upper is stitched to the sole without any further lasting of the pulled-over portions than that performed in the sewing operation, the tacks remaining in positions to hold the upper closely in the angle between the last and the projecting margin of the sole under the tension applied in the pulling-over operation until it has thus been permanently secured to the sole. After the sewing operation the tacks will be withdrawn.

It will be evident that by the use of the machine described the upper is stretched more uniformly and tightly over the last than has been possible heretofore in the progressive lasting of a previously unstretched upper, with a resulting improvement in the quality of the work and a substantial saving in upper stock, as hereinbefore explained.

It is to be understood that the machine described is by no means limited in utility to the manufacture of shoes having unlined uppers and having two soles arranged as herein illustrated, but that it may be also used, as hereinbefore suggested, in the manufacture of various other kinds of stitchdown shoes. It is further to be understood that the invention is not limited to means for driving the particular number of tacks herein shown nor means for driving the tacks in the precise locations indicated.

Having described the invention, what I claim as new and desire to secure by Letters Patent of the United States is:

1. In a machine for shaping over lasts the uppers of stitchdown shoes, the combination with means for shaping an upper over the forepart of a last, of means for driving upper-holding fastenings through the upper and into the last at the end of the toe and the opposite sides of the forepart in such relation to the bottom face of the last as to permit the margin of the upper to extend outwardly upon the projecting margin of a sole while the fastenings are in upper-holding positions.

2. In a machine for pulling over lasts the uppers of stitchdown shoes, the combination with a plurality of grippers for pulling an upper over a last respectively at the end of the toe and at the opposite sides of the fore-

part, of a plurality of upper-fastening devices arranged to drive upper-holding fastenings through the upper and into the last at the end of the toe and the sides of the forepart in such relation to the bottom face of the last as to permit the margin of the upper to extend outwardly upon the projecting margin of a sole while the fastenings are in upper-holding positions.

3. In a machine for shaping over lasts the uppers of stitchdown shoes, the combination with means for shaping an upper over the forepart of a last, of a plurality of upper-fastening devices movable into upper-fastening positions after the upper-shaping operation and arranged to drive upper-holding fastenings through the upper and into the last in different locations about the forepart in such relation to the bottom face of the last as to permit the margin of the upper to extend outwardly upon the projecting margin of a sole while the fastenings are in upper-holding positions.

4. In a machine for shaping over lasts the uppers of stitchdown shoes, the combination with means for shaping an upper over a last, of means for driving upper-holding fastenings through the upper and into the last at its opposite sides in such relation to the bottom face of the last as to permit the margin of the upper to extend outwardly upon the projecting margin of a sole while the fastenings are in upper-holding positions.

5. In a machine for pulling over lasts the uppers of stitchdown shoes, the combination with grippers for pulling an upper over a last at the opposite sides of the forepart at one operation, of upper-fastening devices constructed and arranged to act automatically to drive upper-holding fastenings through the upper and into the last at the opposite sides of the forepart in such relation to the bottom face of the last as to permit the margin of the upper to extend outwardly upon the projecting margin of a sole while the fastenings are in upper-holding positions.

6. In a machine for pulling over lasts the uppers of stitchdown shoes, the combination with grippers for pulling an upper over a last in different locations about the forepart of the last, of a plurality of upper-fastening devices mounted independently of said grippers and arranged to drive upper-holding fastenings through the upper and into the last in such relation to the bottom face of the last as to permit the margin of the upper to extend outwardly in substantially parallel relation to the projecting margin of a sole while the fastenings are in upper-holding positions.

7. In a machine for pulling over lasts the uppers of stitchdown shoes, the combination with grippers for pulling an upper over a last in different locations about the forepart of the last, of a plurality of upper-fastening

- devices movable relatively to said grippers into upper-fastening positions and arranged to drive upper-holding fastenings through the upper and into the last in such relation to the bottom face of the last as to permit the margin of the upper to extend outwardly upon the projecting margin of a sole while the fastenings are in upper-holding positions.
8. In a machine for pulling over lasts the uppers of stitchdown shoes, the combination with means for pulling an upper over the forepart of a last, of a plurality of tackers movable relatively to the upper-pulling means into operative positions and arranged to drive upper-holding tacks part way into the shoe and last in such relation to the bottom face of the last as to permit the margin of the upper to extend outwardly in substantially parallel relation to the projecting margin of a sole while the tacks are in upper-holding positions.
9. In a machine for pulling over lasts the uppers of stitchdown shoes, the combination with means for pulling an upper over the forepart of a last with its margin extending heightwise of the last, of means for driving upper-holding fastenings through the upper and into the last in different locations about the forepart in such relation to the bottom face of the last as to permit the margin of the upper thus pulled to be turned outwardly to lie upon the projecting margin of a sole applied over the bottom of the last while the fastenings are in upper-holding positions.
- 35 10. In a machine for pulling over lasts the uppers of stitchdown shoes, the combination with grippers for pulling an upper over the forepart of a last with its margin extending heightwise of the last, of upper-fastening devices movable relatively to said grippers into upper-fastening positions and arranged to drive upper-holding fastenings through the upper and into the last in different locations about the forepart in such relation to the bottom face of the last as to permit the margin of the upper thus pulled to be turned outwardly in substantially parallel relation to the projecting margin of a sole applied over the bottom of the last while the fastenings are in upper-holding positions.
11. In a machine for pulling over lasts the uppers of stitchdown shoes, the combination with grippers for pulling an upper respectively at the end of the toe and at the opposite sides of the forepart with the margin of the upper extending heightwise of the last, of a plurality of tackers arranged to drive upper-holding tacks part way into the shoe and last at the end of the toe and the sides of the forepart in such relation to the bottom face of the last as to permit the margin of the upper to be turned outwardly to lie upon the projecting margin of a sole applied over the bot-
- tom of the last while the tacks are in upper-holding positions.
12. In a machine for shaping over lasts the uppers of stitchdown shoes, the combination with means for shaping an upper over a last, of means for driving upper-holding fastenings through the upper and into the last at the opposite sides of the last in locations substantially at the junction of the bottom face and the upper-shaping surface of the last and in such relation to said bottom face as to permit the margin of the upper to extend outwardly upon the projecting margin of a sole while the fastenings are in upper-holding positions.
13. In a machine for pulling over lasts the uppers of stitchdown shoes, the combination with means for pulling an upper over the forepart of a last, of a plurality of upper-fastening devices arranged to drive upper-holding fastenings through the upper and into the last in different locations about the forepart substantially at the junction of the bottom face and the upper-shaping surface of the last and in such relation to said bottom face as to permit the margin of the upper to be turned outwardly in angular relation to the portion of the upper adjacent thereto on the upper-shaping surface of the last while the fastenings are in upper-holding positions.
14. In a machine for pulling over lasts the uppers of stitchdown shoes, the combination with grippers for pulling an upper over a last in different locations about the forepart, of a plurality of tackers arranged to drive upper-holding tacks part way into the shoe and last in different locations about the forepart substantially at the junction of the bottom face of the upper-shaping surface of the last and at inclinations to said bottom face such as to permit the margin of the upper to be turned outwardly in angular relation to the portion of the upper adjacent thereto on the upper-shaping surface of the last while the tacks are in upper-holding positions.
15. In a machine of the class described, the combination with means for shaping an upper over the forepart of a last, of means for driving upper-holding fastenings through the upper and into the last at the opposite sides of the forepart in locations beyond but near the bottom face of the last.
16. In a machine of the class described, the combination with means for shaping an upper over the forepart of a last, of means for driving upper-holding tacks part way into the shoe and last in different locations about the forepart beyond but near the bottom face of the last and in inclined relation to said bottom face.
17. In a machine of the class described, the combination with means for shaping an upper over the forepart of a last, of means for driving upper-holding fastenings through

the upper and into the last in different locations about the forepart substantially at the junction of the bottom face and the upper-shaping surface of the last.

5 18. In a machine of the class described, the combination with grippers for pulling an upper over a last in different locations about the forepart, of upper-fastening devices movable relatively to said grippers into

10 upper-fastening positions and arranged to drive upper-holding fastenings through the upper and into the last in different locations about the forepart, said upper-fastening devices having means for limiting their posi-

15 tioning movements as determined by the last to locate the fastenings substantially at the junction of the bottom face and the upper-shaping surface of the last.

19. In a machine of the class described, 20 the combination with grippers for pulling an upper over a last in different locations about

the forepart, of upper-fastening means comprising a plurality of tackers arranged to drive upper-holding tacks part way into the

25 shoe and last in different locations about the forepart substantially at the junction of the bottom face and the upper-shaping surface of the last and in directions inclined to said bottom face.

30 20. In a machine of the class described, the combination with means for pulling an upper over the forepart of a last, of means for fastening the upper in different locations about the forepart comprising a plurality of

35 tackers movable relatively to the upper-pulling means into positions determined by the last and arranged to drive tacks part way into the shoe and last in locations substantially at the junction of the bottom face and the 40 upper-shaping surface of the last and in directions inclined to said bottom face.

21. In a machine of the class described, the combination with means for shaping an upper over the forepart of a last, of a plurality of tackers movable into upper-fastening positions and arranged to drive upper-holding tacks part way into the shoe and last in different locations about the forepart and in directions inclined to the bottom face of

45 the last, said tackers having thereon stops arranged to limit their positioning movements as determined by the last to locate the tacks substantially at the junction at the bottom face of the upper-shaping surface of 50 the last.

55 22. In a machine of the class described, the combination with grippers for pulling an upper over a last respectively at the end of the toe and the opposite sides of the forepart,

60 of upper-fastening means comprising a plurality of tackers movable relatively to said grippers into upper-fastening positions and constructed and arranged to drive tacks part way into the shoe and last at the end of the

65 toe and the sides of the forepart, said tackers

having stops thereon for limiting their positioning movements in such relation to the last as to locate the tacks substantially at the junction of the bottom face and the upper-shaping surface of the last.

70 23. In a machine of the class described, the combination with means for pulling an upper over the forepart of a last, of means for fastening the upper in different locations about the forepart comprising a plurality of 75 driver bars movable in directions heightwise of the last and a plurality of drivers operated by said driver bars and movable in directions inclined to the bottom face of the last to drive fastenings through the upper and into the last, and means for determining such a relation between said drivers and the last as to drive the fastenings substantially at the junction of said bottom face and the upper-

80 shaping surface of the last.

85 24. In a machine of the class described, the combination with means for pulling an upper over a last, of an arm movable toward the last and having thereon a plurality of upper-

90 fastening devices arranged to drive fastenings through the upper and into the last, said upper-fastening devices being so mounted on the arm as to permit relative movement between them to position them in proper relation to the last and having means for automatically positioning them as determined by the last to locate the fastenings substantially at the junction of the bottom face and the upper-shaping surface of the last.

95 25. In a machine for pulling over lasts the uppers of stitchdown shoes, the combination with a gripper for pulling an upper over a last, of upper-fastening means movable relatively to said gripper into upper-fastening

100 position and constructed and arranged to drive an upper-holding fastening through the upper and into the last in such relation to the bottom face of the last as to permit the margin of the upper to extend outwardly over the projecting margin of a sole while the fastening is in upper-holding position.

105 26. In a machine for pulling over lasts the uppers of stitchdown shoes, the combination with means for pulling an upper over a last with its margin extending heightwise of the last, of means for driving an upper-holding fastening through the upper and into the last in such relation to the bottom face of the last as to permit the margin of the upper to be

110 turned outwardly to lie upon the projecting margin of a sole applied over the bottom of the last while the fastening is in upper-holding position.

115 27. In a machine for pulling over lasts the uppers of stitchdown shoes, the combination with a gripper for pulling an upper over a last with its margin extending heightwise of the last, of upper-fastening means comprising a tacker movable relatively to said gripper into upper-fastening position and constructed

120

125

130

and arranged to drive a tack part way into the shoe and last in such relation to the bottom face of the last as to permit the margin of the upper to be turned outwardly to 5 lie upon the projecting margin of a sole applied over the bottom of the last while the tack is in upper-holding position.

28. In a machine for pulling over lasts the uppers of stitchdown shoes, the combination 10 with means for pulling an upper over a last with its margin extending heightwise of the last, of means for driving an upper-holding fastening part way into the shoe and last in a location substantially at the junction of the 15 bottom face and the upper-shaping surface of the last and at an inclination to said bottom face such as to permit the margin of the upper to be turned outwardly in angular relation to the portion of the upper adjacent 20 thereto on the upper-shaping surface of the last while the fastening is in upper-holding position.

29. In a machine for pulling over lasts the uppers of stitchdown shoes, the combination 25 with a gripper for pulling an upper over a last, of upper-fastening means comprising a tacker movable relatively to said gripper into upper-fastening position and constructed and arranged to drive a tack part way into 30 the shoe and last in a location substantially at the junction of the bottom face and the upper-shaping surface of the last and in such relation to said bottom face as to permit the margin of the upper to be turned outwardly 35 to lie upon the projecting margin of a sole applied over the bottom of the last while the tack is in upper-holding position.

30. In a machine of the class described, the combination with means for shaping an upper over the forepart of a last, of means for driving a fastening through the upper and into the forepart of the last in a location beyond but near the bottom face of the last and in a direction inclined to said bottom face.

45 31. In a machine of the class described, the combination with means for shaping an upper over a last, of means for driving an upper-holding tack part way into the shoe and last substantially at the junction of the 50 bottom face and the upper-shaping surface of the last and in a direction inclined to said bottom face.

32. In a machine of the class described, the combination with means for pulling an upper over a last, of upper-fastening means movable relatively to the upper-pulling means into upper-fastening position and constructed and arranged to drive a fastening through the upper and into the last in a location substantially at the junction of the bottom face and the upper-shaping surface of the last. 75

33. In a machine of the class described, the combination with a gripper for pulling an upper over a last, of upper-fastening means comprising a tacker movable relatively to the gripper into upper-fastening position and constructed and arranged to drive a tack part way into the shoe and last in a direction inclined to the bottom face of the last, and means for limiting the positioning movement of said tacker as determined by the last to locate the tack substantially at the junction of the bottom face and the upper-shaping surface of the last. 80

34. In a machine of the class described, the combination with means for pulling an upper over a last, of a tacker movable into upper-fastening position and constructed to drive an upper-holding tack part way into the shoe and last in a direction inclined to the bottom face of the last, said tacker having thereon a stop for engaging the shoe to limit its positioning movement in such relation to the last as to locate the tack substantially at the junction of the bottom face and the upper-shaping surface of the last. 95

35. In a machine of the class described, the combination with means for pulling an upper over a last, of means for fastening the upper comprising a driver bar movable in a direction heightwise of the last and a driver operated by said driver bar and movable in a direction inclined to the bottom face of the last to drive a fastening through the upper only and into the last in a location substantially at the junction of said bottom face with the upper-shaping surface of the last. 105

In testimony whereof I have signed my name to this specification.

JAMES M. MATHEU. 115
